UNITED STATES PATENT OFFICE.

DAVID YOUNG, OF ANGLESEA, NEW JERSEY.

SASH-FASTENER.

SPECIFICATION forming part of Letters Patent No. 508,361, dated November 7, 1893.

Application filed June 17, 1893. Serial No. 477,997. (No model.)

To all whom it may concern:

Be it known that I, DAVID YOUNG, a citizen of the United States, and a resident of Anglesea, in the county of Cape May and State 5 of New Jersey, have invented certain new and useful Improvements in Sash-Locks or Fasteners for Windows; and I do hereby declare the following to be a full, clear, and exact description of the invention, such as will enable others skilled in the art to which it appertains to 10 make and use the same.

This invention relates to sash-locks or fasteners for windows, especially adapted for car-windows, and has for its object to provide a 15 device of the character set forth which is strong and durable and will stand vibratory force and shocks or blows incident to the jarring and jolting of a moving car without becoming injured or impaired, and will thereby 20 always insure a ready operation without the inconveniences and disadvantages usually attendant upon the fastenings of car-windows.

With these and other objects in view, the invention consists of the construction and arrangement of the several parts as will be more 25 fully hereinafter described and claimed.

In the drawings: Figure 1 is a front elevation of a car-window frame and sash broken away at several points and showing the improved lock or fastener applied thereto. Fig. 2 is a section on the line $x-x$ Fig. 4, showing the lock or fastener operated to release the bolt for the purpose of raising the sash. Fig. 3 is a view similar to Fig. 2 with the bolt in 30 locked position. Fig. 4 is a transverse vertical section on the line $y-y$ Fig. 1. Fig. 5 is a detail perspective view of parts of the lock or fastener disassembled.

Similar numerals of reference are employed 40 to indicate corresponding parts in the several figures of the drawings.

Referring to the drawings, the numeral 1 designates the sash frame having the customary sash-grooves in opposite sides thereof in 45 one of which is formed a series of recesses 2 and thereover is fixed a metallic wear strip 3 having openings 4 therein aligning with the said recesses 2. The lower part of the right of the sash is provided with a mortise 5 having a front opening 6 and at the edge is supplied with a bolt opening 7. Over the said bolt

opening is mounted an escutcheon plate 8 having an opening therein aligning with the said bolt opening 7 and acting to hold the bolt in proper position and take up wear. 55

To the outer lower side of the sash is secured a tubular sleeve 9 having an inner integral collar 10 that bears against the sash and in advance of the said collar the said sleeve is formed with a pair of oppositely disposed lugs 60 11. Within the said sleeve 9 is located a push-bar 12 having an outer shouldered collar 13 which is movably fitted in the said sleeve and formed with an outer flanged head 14 provided with a milled edge, the said flanged head limiting the inward movement of the collar 13 and the push-bar 12. The push-bar 12 is surrounded by a coiled spring 15 which has its inner end bearing against the lugs 11 and its outer end against the shouldered collar 13, the 65 normal tendency of the said spring being to force the said collar outwardly as will be readily understood. Pivotedly mounted between the lugs 11, is a bell-crank lever 16, having a cam-arm 17 with a stud or post 18, rising therefrom, and a cam-lug 19 in rear of the said stud or post. The other arm, 20, of the said bell-crank lever is formed of about the same thickness as the greater part of the said cam-arm, and is supplied with an opening 21 near the 70 end thereof. The elbow of the said lever has an opening 22 therethrough through which extends a rigidly mounted pin 23, whose opposite ends are secured in the said lugs 11 and on which the bell-crank lever freely turns. 75 The inner end of the push-bar 12 is flattened and formed to somewhat resemble a cam to engage the curved edge of the cam-lug 19 which is adjacent thereto for the purpose of properly operating the bell-crank lever. The said 80 inner end of the push-bar is formed with an opening 24, through which the stud or pin 18 passes to provide a pivotal connection of the two parts. 85

To the arm 20 of the bell-crank lever is pivotally connected the inner bifurcated end 25 of a slide-bolt 26, the said slide bolt being normally disposed in a plane at a right angle to the plane of the push-bar 12, and has its outer end beveled as at 27 for evident and well-known purposes. This slide-bolt is mounted 90 in the opening 7 of the sash and is adapted to 100

have bearing in the escutcheon 8, and engage the recesses 2 for holding the sash in its adjusted position. When the collar 13 and head 14 thereof are free to be influenced by the 5 spring 15 the bolt 26 occupies a normal locked position, as the said spring exerting its force on the push-bar 12 through the collar 13 draws the cam-arm 17 of the bell-crank lever outwardly and through the arm 20 of said lever 10 toward the sash frame and consequently moves the slide-bolt in a similar direction. By the intervention of the said bell-crank lever it will be observed that the spring 15 is caused to act reversely on the slide-bolt in view of the operation 15 of springs of a similar character usually employed with sash-locks or fasteners for car-windows. On pressing the push-bar 12 inwardly as shown in Fig. 2 the adjacent bearing edge of the cam-lug 19 is engaged 20 firmly by the inner end of the said push-bar and the bell-crank lever is thereby operated on its pivot to move the arm 20 backwardly from the sash-frame and retract the slide-bolt 26 to permit the sash to be raised. The provision 25 of the cam-lug relieves the stud or post 18 of a part of the wear and tension which would otherwise be brought to solely bear thereon. It will also be seen that in raising the sash the sleeve 9 may be effectually used 30 as a grip in addition to the ordinary finger grip which will be provided as shown in Fig. 1, and the movement of the operator to release the slide-bolt, being an inward push, instead

of an outward pull, the sash may the more readily and quickly be raised.

While the device is shown applied to a car-window, it will be understood that it can be as readily employed in connection with any other form of sash and in all forms of application thereof, such changes that lie within the scope of the invention together with a variation in the proportions might be made and substituted for those shown and described without in the least departing from the nature or spirit of the invention.

Having thus described the invention, what is claimed as new is—

In a sash lock or fastener, the combination of a spring actuated push bar, a slide bolt disposed at a right angle thereto, and a bell crank lever connected to the inner end of said slide bolt and push bar, and having a projecting cam lug with which the inner end of said bar is adapted to engage said cam lug, being located on the outer side of the bell crank lever having its bearing edge corresponding in contour to the inner end of the push bar, substantially as described.

In testimony whereof I have signed this specification in the presence of two subscribing witnesses.

DAVID YOUNG.
